TELEPHONE COMMUNICATING SYSTEM

Andrew J. Sorensen, Edgewood, and Leland D. Whitelock, Wilkinsburg, Pa., assignors to The Union Switch & Signal Company, Swissvale, Pa., a corporation of Pennsylvania

Application January 28, 1933, Serial No. 654,004
Renewed June 9, 1934

19 Claims. (Cl. 179—82)

Our invention relates to telephone communicating systems, and particularly to carrier current telephone systems for communication on railway trains.

5 We will describe one form of apparatus embodying our invention, and will then point out the novel features thereof in claims.

Systems have been proposed for telephoning between a wayside station and a railway train, 10 or between two trains, or between two locations on the same train, over a communicating circuit including the traffic rails such, for example, as disclosed in the L. O. Grondahl application Serial No. 450,135, filed May 6, 1930, for Electric train 15 signaling systems. For such telephone systems, it has been proposed to modulate a carrier frequency current at voice frequencies and then to suppress the carrier and one side band, supplying the communicating circuit with the remaining side band only. At the receiving location, 20 the transmitted side band is first combined with a local carrier and demodulated; and the resulting audio frequencies are then amplified and supplied to a telephone receiver or loud speaker. In 25 such systems the outgoing current is amplified to a relatively high energy level, and the receiving apparatus includes an amplifier of high gain. To provide the necessary two-way operation, separate receiving and transmitting equipments are 30 installed at each location, together with switching apparatus to selectively transfer the communicating circuit from one equipment to the other. The switching apparatus set forth in our present application to selectively transfer the 35 communicating circuit between the transmitting and the receiving equipments is somewhat similar to the switching apparatus set forth in the copending application for Communication systems, Serial No. 729,806, filed June 9, 1934, by Leland D. Whitelock et al., and which pending application contains claims directed to such switching apparatus.

A feature of our invention is the provision of 40 new and novel apparatus for a carrier current telephone system wherewith both the receiving and the transmitting equipments at a location utilize the same apparatus for amplifying, modulating and demodulating. To state it another way, in systems embodying our invention, a major portion of the equipment at a location is made 45 to do double duty by functioning in both the sending and the receiving of a telephone message. Other features of our invention will appear as the specification progresses.

50 The accompanying drawing is a diagrammatic

view of one form of apparatus embodying our invention, and this apparatus is particularly adapted to telephone systems for railway trains. It will be understood, however, that we do not limit ourselves to telephone systems for railway trains, 5 but our invention is equally useful for other carrier systems of telephoning. The form of apparatus here disclosed will serve to illustrate the different forms of apparatus embodying our invention.

10 In the accompanying drawing, the reference characters 2 and 3 designate inductor coils mounted on a railway train in inductive relation with the traffic rails 1 and 1^a, respectively. To clarify the following description, it will be considered that telephone communication between the locomotive and the caboose of a freight train is to be provided, and hence, both the locomotive and the caboose will be equipped with the apparatus here disclosed, and a pair of inductor coils 20 2 and 3 will be mounted both on the locomotive and on the caboose. These inductor coils 2 and 3 are adapted to be connected to the input of a receiver AR, or to the output of a transmitter AT, by means of a manually operated circuit 25 controller 4. With the circuit controller 4 in engagement with a contact 5, the coils 2 and 3 are connected to the receiver AR by a circuit that extends from the right-hand terminal of the coil 3 over wire 6, contact 4—5, filter F1, tuning condenser 7, and wire 8 to the left-hand terminal of coil 2, the two coils 2 and 3 being connected in series. The filter F1 is connected to the input 30 of an amplifier AM by wires 10 and 11, and the output of the amplifier AM is connected over 35 wires 13 and 14 to the primary winding 12 of a coupling transformer T2 to be referred to later.

The filter F1 is preferably a band-pass filter so proportioned and adjusted as to pass a carrier current side band having a width equal to the 40 voice frequency range. The amplifier AM may be any one of several types adapted to amplify the side band frequencies passed to its input by the filter F1. The specific type of neither the filter F1, nor of the amplifier AM forms a part of 45 our invention, and these devices are shown conventionally only in order to simplify the drawing.

Raising the circuit controller 4 into engagement with a contact 15 connects the inductor coils 2 and 3 with the output of the transmitter 50 AT, the circuit extending from the right-hand terminal of coil 3, along wire 6, contact 4—15 tuning condenser 16, secondary winding 17 of an output transformer T10 of transmitter AT, and wires 18 and 8 to the left-hand terminal of 55

coil 2. It follows that in the lower or normal position of the circuit controller 4, where it is in engagement with contact 5, the communicating circuit is coupled with the receiver AR through the medium of the coils 2 and 3; and in the upper or reverse position of the circuit controller 4, where it engages the contact 15, the coils 2 and 3 form a coupling between the traffic rails 1 and 1^a of the communicating circuit and the transmitter AT.

It has been proposed for train telephone systems to carry the microphone, designated in the drawing by the reference character M, in a rack, not shown, where it is normally inactive. The microphone is rendered active to transmit a telephone message by the operator moving a handle 19 to the right in the drawing, to a position indicated by a dotted line. As shown schematically, the circuit controller 4 and a second circuit controller 20 are both connected to and operated by the handle 19. Moving handle 19 to the right operates the circuit controller 4 from engagement with contact 5 into engagement with contact 15, and also operates the controller 20 into engagement with a contact 21. Moving the handle 19 from the dotted line position back to the position shown by the solid lines in the drawing, operates the controllers 4 and 20 to the positions shown in the drawing. As pointed out above, the normal position of controller 4 connects the coils 2 and 3 to the receiver AR, and the reverse position of controller 4 transfers the coils 2 and 3 to the transmitter AT. The reverse position of controller 20 makes engagement with the contact 21 and completes a circuit easily traced for energizing a series of relays 22, 23, 24, 25 and 26 in parallel. It follows that as long as the microphone M is inactive and the handle 19 is in its normal position, the traffic rails 1 and 1^a are coupled to the receiver AR, and the relays 22, 23, 24, 25 and 26 are deenergized; and the moving of the handle 19 preparatory to rendering the microphone active couples the traffic rails 1 and 1^a with the transmitter AT, and energizes the above series of relays.

A first stage amplifier, designated as a whole by the reference character AM1, is provided to amplify the voice frequencies of a telephone message it is desired to transmit, or to amplify the side band frequencies of a carrier modulated with the voice frequencies of a telephone message which is to be received, the energy amplified in either case being supplied to the input of a frequency translating unit FTU to be described later. The amplifier AM1 includes an electron tube 27 having a plate 28, a grid 29 and a filament 30, the filament 30 being heated by a battery 31. With the relay 22 deenergized and its back contact 32 closed, the grid 29 is connected to the secondary winding 33 of the coupling transformer T2, a biasing element comprising a resistor 34 and a condenser 35 in parallel being inserted in the connection between the opposite terminal of the secondary winding 33 and the filament 30. Energizing relay 22 to close its front contact 36 transfers the grid 29 to a circuit that includes the secondary winding 37 of a coupling transformer T4 as will be understood by an inspection of the drawing. The primary 38 of transformer T4 is connected to the microphone M through a battery 39, and transformer T4 is so proportioned as to match the impedance of the microphone to the grid impedance of tube 27.

The plate 28 of tube 27 is normally connected

to the primary winding 40 of a coupling transformer T4 of the frequency translating unit FTU over a back contact 41 of the relay 22, and is transferred to the primary winding 42 of a coupling transformer T3 of the translating unit FTU over the front contact 43 of relay 22 when that relay is energized. To be explicit, the normal plate circuit for tube 27 can be traced from the positive terminal of a convenient source of current such as a battery 44 along wire 45, primary 10 winding 40 of transformer T4, back contact 41, plate 28, filament 30, biasing element 34-35, a ground connection 47, and thence by a ground connection 48 to the negative terminal of battery 44. With the relay 22 picked up, this plate 15 circuit extends from the positive terminal of battery 44 along wire 45, primary winding 42 of transformer T3, wire 49, front contact 43, and thence as before traced to the negative terminal of battery 44. It follows that the output of amplifier AM1 is normally supplied to the coupling transformer T4 of the frequency translating unit FTU, and is transferred to the transformer T3 of the translating unit FTU by the energizing of the relay 22. That is to say, in the normal 20 position of handle 19, frequencies of a given side band when picked up from the traffic rails and supplied to the receiver AR are passed by the receiver AR to the transformer T2 and are applied to the grid of the tube 27; and hence are 25 repeated in the transformer T4 of the translating unit FTU with greatly increased amplitude. The reverse position of handle 19 energizes the relay 22 and under this condition, voice variations developed by speaking into the microphone 30 M induce corresponding frequencies in the secondary of the transformer T4 which are applied to the grid circuit of tube 27, and are repeated in the primary of the transformer T3 of the translating unit FTU greatly increased in amplitude. 35

The frequency translating unit FTU includes a generator of carrier current, a push-pull balanced modulator circuit in which the carrier frequency is modulated at voice frequencies and then balanced out, a push-pull balanced demodulator circuit in which the carrier current is 40 added to a side band and then balanced out, a band-pass filter in which the desired side band to be transmitted is selected, and a low-pass filter to pass the desired audio frequencies. This 45 frequency translating unit will now be described. The electron tubes 50 and 51 are preferably standard three-element tubes, the filaments 52 of which are heated by a battery 53. Normally the grid 55 of tube 50 is provided with a circuit 50 that extends from the grid 55 over back contact 56 of relay 23, upper half of the secondary winding 57 of transformer T4, wire 58, resistor 59, biasing battery 60, and filament 52 of tube 50. Normally the grid circuit for the tube 51 extends 55 from its grid 61 over back contact 62 of relay 23, lower half of secondary winding 57 of transformer T4, wire 58, resistor 59, battery 60, and filament 52 of tube 51. At such time as relay 23 is energized and its front contacts 63 and 64 60 are closed, the grid 55 of tube 50 is connected to the upper half of the secondary winding 65 of transformer T3 over the front contact 63, and the grid 61 of tube 51 is connected to the lower 65 half of the secondary winding 65 over the front contact 64 as will be readily understood by an 70 inspection of the drawing. The secondary winding 57 of transformer T4 is one continuous winding with the wire 58 connected with the center 75 turn; the secondary winding 65 of transformer

T₃ is similarly wound. It is clear from the foregoing description of the grid circuits for tubes 50 and 51 that alternating voltages induced in either the secondary winding 57 of transformer T₄, or in the secondary winding 65 of transformer T₃ will cause the grids 55 and 61 to have unlike polarities.

The electron tube 66 is preferably of the three-element type, and is provided with a plate circuit extending from the positive terminal of battery 44 along wire 45, inductor coil 67, plate 68, filament 69, and ground connections 70 and 48 back to battery 44. An oscillating circuit 71 including an inductor 72 and a condenser 73, is connected with the plate circuit of tube 66 through a blocking condenser 74 and to the grid 75 of tube 66 through a biasing element 76, an intermediate terminal of inductor 72 being connected to the filament 69 by a wire 77. The parts of the oscillating circuit 71 are so proportioned and adjusted as to generate a carrier frequency current of say 7000 cycles per second. It will be understood, of course, that other carrier frequencies could be selected if found desirable. The oscillating circuit 71 is coupled to the grid circuits of tubes 50 and 51 through a coupling condenser C₃ and wire 78, the resistor 59 acting as a load resistance for the oscillating circuit. It is to be noted that the carrier voltages supplied by oscillating circuit 71 to the grids 55 and 61 are in phase, whereas, the voltages supplied to the grids 55 and 61 by the transformers T₃ and T₄ are opposite in phase.

At such time as relay 24 is deenergized and its back contacts 79 and 80 are closed, the plates 81 and 82 of tubes 50 and 51, respectively, are connected with the opposite terminals of the primary winding 83 of a transformer T₆ in the conventional push-pull arrangement. The plate circuit for tube 50 extends from the positive terminal of battery 44 along wire 45, upper half of primary winding 83, back contact 79, plate 81, filament 52, thence by ground connections 46 and 48 back to the battery 44; and the plate circuit for the tube 51 includes positive terminal of battery 44, wire 45, the lower half of the primary winding 83, back contact 80, plate 82, filament 52 of tube 51, and ground connections 46 and 48 back to the battery 44. At such time as relay 24 is energized and its front contacts 84 and 85 are closed, the plate circuit of tube 50 includes the upper half of the winding 86 of an autotransformer T₅, and front contact 84; and the plate circuit of tube 51 includes the lower half of winding 86 and front contact 85.

Condensers C₁ and C₂ are connected across the upper and lower halves of the secondary winding 65 of transformer T₃ and serve as balancing condensers for balancing the carrier voltages on the grids 55 and 61 when transformer T₃ is active during the transmitting of voice frequencies as will appear when the operation of the system is described. The transformer T₄ is so proportioned as to pass the carrier side band frequencies, whereas, the transformer T₃ is so proportioned as to pass the voice frequencies. Condensers C₄ and C₅ are connected across the two half windings of the primary 83 of transformer T₆ and function as balancing condensers to balance out the carrier voltages passed to the plate circuits of tubes 50 and 51, during the receiving of a telephone message.

The addition and subtraction of the carrier voltages and the voice frequency voltages supplied by the transformer T₃, when applied to the grids

of the tubes 50 and 51 produce a plate circuit current having the upper and lower side band frequencies of the carrier, and the carrier is suppressed by the differential connection of the windings of transformer T₅. The addition and subtraction of the carrier voltages and the side band frequency voltages supplied by the transformer T₄ when applied to the grids of tubes 50 and 51 demodulate the side band and produce in the plate circuits audio frequencies. That is to say, the voice frequencies supplied by the transformer T₃ modulate the carrier current and the carrier is balanced out leaving only the upper and lower side bands. The side band voltage supplied through transformer T₄ when combined with the carrier is demodulated and the carrier balanced out leaving only audio frequencies and other products of demodulation. In other words, in one condition, the voice frequencies are translated along a frequency scale to side bands of a carrier frequency having a width equal to the voice frequency range; and a side band of the carrier having a width equal to the voice frequency range is translated down the frequency scale to audio frequencies in the other condition.

Winding 86 of the auto-transformer T₅ is included in the input of a band-pass filter BPF, and the secondary winding 87 of the transformer T₆ is included in the input of a low-pass filter LPF. The band-pass filter BPF may be any one of several well known types and is so proportioned and adjusted as to eliminate one side band of the carrier, and to transmit the other side band. The side band to be transmitted is supplied to the output circuit of the translating unit FTU which is coupled to the input of a second stage amplifier AM₂. The low-pass filter LPF may be any one of several well known types and is so proportioned and adjusted as to pass the audio frequencies, and to remove unwanted products of demodulation. The audio frequencies passed by the filter LPF are supplied to the output circuit of the translating unit FTU. As the specific type of neither the band-pass filter BPF, nor of the low-pass filter LPF forms a part of our invention, these devices are shown conventionally only for clarity.

The output of the frequency translating unit FTU is coupled to the input of the amplifier AM₂ over either the front contact 88 of relay 25 or over the back contact 89 of that relay. Under the normal deenergized condition of relay 25, the output of unit FTU includes the low-pass filter LPF, back contact 89, condenser C₆, a portion of winding 90 of an auto-transformer T₇, condenser C₇, and wire 91. With relay 25 energized, the output of unit FTU includes band-pass filter BPF, front contact 88, and thence as before traced. Electron tube 92 of amplifier AM₂ is preferably of the three-element type having its filament 93 heated by a battery 94. The grid 95 of tube 92 is provided with a circuit that includes the winding 90 of transformer T₇ and a biasing battery 96, a condenser 97 being connected across the battery 96 to by-pass alternating voltages. When relay 26 is deenergized, the plate circuit for the tube 92 can be traced from the positive terminal of battery 44 along wire 98, primary winding 99 of a transformer T₈, back contact 100 of relay 26, plate 101, filament 93, 70 and thence by ground connections 102 and 48 back to the battery 44. With relay 26 picked up, this plate circuit includes battery 44, wire 98, primary winding 103 of a transformer T₉, front contact 104, and then as before traced. 75

The secondary winding 105 of transformer T8 is connected directly to a loud speaker LS. The two half sections of the secondary winding 106 of the transformer T9 are connected to the grids 5 107 and 108 of tubes 109 and 110, respectively, of the transmitter AT, biasing batteries 111 and 112 being inserted in the connection as will be readily understood by an inspection of the drawing. It follows that the audio frequencies amplified by 10 amplifier AM2 will be reproduced in the loud speaker, and that the side band frequencies amplified by amplifier AM2 are utilized to excite the grid elements of the tubes of the transmitter. The plates 113 and 114 of tubes 109 and 110 are 15 connected through the two half sections of the primary winding 115 of the output transformer T10 to the terminal B of a convenient source of current in the conventional push-pull arrangement, the opposite terminal N of the source being connected to the filaments of the tubes. Hence, the side band frequencies applied to the grids of tubes 109 and 110 are supplied to the communicating circuit through transformer T10 20 at a relatively high energy level.

25 In describing the operation of our system, we shall first assume that it is desired to transmit a telephone message. The operator will first move the handle 19 to the right preparatory to removing the microphone from the rack, and in so doing the coils 2 and 3 are transferred to the output of the transmitter AT and the relays 22, 23, 24, 25 and 26 are all energized. The variations developed by speaking into the microphone M induce corresponding frequencies in the secondary 37 of transformer T1. These voice frequencies are applied to the grid of the amplifying tube 27 and are repeated in its plate circuit which includes the primary winding 42 of transformer T3 greatly increased in amplitude. The 30 combination of the voice frequencies induced in the secondary 65 of transformer T3 with the carrier frequencies generated by the tube 66 and its related circuits produces a modulation of the carrier current. This addition and subtraction of the voice voltages with the carrier voltages on the grids of tubes 50 and 51 produce in the plate circuit of these tubes side band frequencies of the carrier, the carrier being suppressed or balanced out by the differential connection of the windings 45 of transformer T5. That is, the voice frequencies are translated along the frequency scale and now appear as side bands of the carrier. The side band frequencies are applied to the band-pass filter BPF and one side band is eliminated and 50 the other, preferably the upper side band, is supplied to the output of the translating unit FTU which, in turn, is now coupled to the input of the second stage amplifier AM2. These side band frequencies which now represent the spoken message 55 are applied to the input of the tube 92, and hence are repeated in the transformer T9 greatly increased in amplitude. Corresponding frequencies are induced in the secondary winding 106 of transformer T9 and are applied to the grids of tubes 109 and 110 of the transmitter AT where 60 they are amplified to a relatively high energy level and supplied to the traffic rails 1 and 1^a of the communicating circuit. To sum up, the variations developed by speaking into the microphone are first amplified, then translated along the frequency scale to the upper side band frequencies of a carrier current, further amplified to a relatively high energy level, and finally delivered to the communicating circuit.

70 75 Let us now assume that it is desired to receive

a telephone message. The operator will replace the handle 19 to its normal position and transfer the inductor coils 2 and 3 to the receiver AR, and deenergize the series of relays. The side band frequencies transmitted over the communicating circuit from the apparatus at the other location will be picked up from the traffic rails by the coils 2 and 3 and applied through the filter F1 to the input of the amplifier AM. After being filtered and amplified at the receiver AR, the received side band frequencies are applied to the input of the tube 27 of the first stage amplifier AM1 and repeated in its output greatly increased in amplitude. The side band voltages induced in the secondary 67 of transformer T4 are combined 15 with the carrier voltages generated by the tube 66 and its related circuits and applied to the grids of tubes 50 and 51. The addition and subtraction of the side band voltages with the carrier voltages demodulate the side band and cause 20 to appear in the plate circuit of tubes 50 and 51 audio frequencies and other products of demodulation. The audio frequencies are passed to the low-pass filter LPF where unwanted products of demodulation are further eliminated, and 25 the audio frequencies are then supplied to the input circuit of the amplifier AM2. The amplifier AM2 repeats the audio frequency at the transformer T8, and hence they are delivered to the loud speaker LS which now reproduces the 30 telephone message. That is to say, the side band frequencies which represent the telephone message delivered to the communicating circuit at the second location are picked up from the communicating circuit, filtered, amplified, translated 35 down the frequency scale to audio frequencies, further amplified, and finally delivered to the loud speaker.

Apparatus for a telephone such as here disclosed requires a small number of electron tubes 40 and auxiliary apparatus for the complete receiving and transmitting equipment. The use of the same generator of carrier current for both modulation and demodulation provides a frequency stability that insures both naturalness 45 and intelligibility of the transmitted speech. The switching of the usual audio amplifier of the receiving equipment into the transmitting equipment insures ample power for exciting the grids of the high energy level transmitter. The filaments of all tubes normally heated for receiving eliminates the delay required for heating up the tubes for transmission. This means that as soon as the microphone is removed from its rack, the apparatus is instantly ready to transmit. 55

Although we have herein shown and described only one form of apparatus embodying our invention, it is understood that various changes and modifications may be made therein within the scope of the appended claims without departing from the spirit and scope of our invention.

Having thus described our invention, what we claim is:

1. In combination with a frequency translating means including a pair of electron tubes and a source of a given carrier frequency current, input circuits including the grids of said tubes and having a push-pull arrangement, output circuits including the plates of said tubes and having a push-pull arrangement, means for connecting said source with the grids of said tubes in parallel, sending means including a microphone and a current source for supplying a voice frequency current, a communication circuit, receiv- 75

ing means adapted to pass a side band of said carrier frequency modulated with voice frequencies and including a receiver influenced by the communication circuit, a sending circuit including a transmitter adapted to supply current to the communication circuit, a receiving circuit including a loud speaker, and manually controlled means for selectively coupling either the sending means and the sending circuit with said input and output circuits, respectively, or coupling the receiving means and the receiving circuit with said input and output circuits, respectively.

2. In combination with a frequency translating means including a pair of electron tubes and a source of a given carrier frequency current, input circuits including the grids of said tubes and having a push-pull arrangement, output circuits including the plates of said tubes and having a push-pull arrangement, means for connecting said source with the grids of said tubes in parallel, sending means including a source of current and adapted to supply a low frequency signalling current, a communication circuit, receiving means adapted to pass a side band of said carrier frequency modulated with a low frequency signalling current and including a receiver influenced by the communication circuit, a sending circuit including a transmitter adapted to supply current to the communication circuit, a receiving circuit including a signaling device responsive to low frequencies, and manually controlled means for selectively coupling either the sending means and the sending circuit with said input and output circuits, respectively, or coupling the receiving means and the receiving circuit with the input and output circuits, respectively.

3. In combination; a frequency translating means including a pair of electron tubes each having a plate, a grid and a filament; a first and a second transformer each having a primary and a secondary winding, a relay for selectively connecting the grids to the opposite terminals of the secondary winding of either the first or the second transformer, means for connecting an intermediate terminal of each of said secondary windings with the filaments, a local source of carrier current connected with said intermediate terminals, plate circuits for said tubes having a push-pull arrangement, sending means including a microphone adapted to supply the primary winding of said first transformer with the voice frequencies of a spoken message, a communication circuit, receiving means effectively influenced by said circuit and adapted to pass to the primary winding of said second transformer the side band frequencies of the carrier modulated with voice frequencies of a spoken message, and control means for governing said relay whereby the frequencies produced in the plate circuits are side band frequencies of the carrier modulated with the voice frequencies of the sending means, or are audio frequencies corresponding to the demodulated side band frequencies of the receiving means.

4. In combination with a frequency translating means including a pair of electron tubes each having a plate, a grid and a filament, and a generator of a given carrier frequency current; plate circuits for said tubes having a push-pull arrangement, means for connecting said generator with the grids of said tubes in parallel, sending means including a microphone for supplying the voice frequencies of a spoken message, a communication circuit, receiving means in-

fluenced by said circuit and adapted to pass the side band frequencies of said carrier frequency modulated with voice frequencies, a circuit controller, means including a contact of the controller for connecting the sending means with the grids of said tubes in a push-pull arrangement, other means including a contact of the controller for connecting the receiving means with the grids of said tubes in a push-pull arrangement, and a manually controlled device for selectively operating said controller whereby the voice frequencies of the sending means are translated in the plate circuits to side band frequencies of the carrier or the side band frequencies passed by the receiving means are translated to audio frequencies.

5. In combination; a frequency translating means including a pair of electron tubes each having a plate, a grid and a filament; a first and a second transformer each having a primary and a secondary winding, a first relay for selectively connecting the grids with the opposite terminals of the secondary of either the first or the second transformer, means for connecting an intermediate terminal of each of said secondaries to the filaments, a local source of carrier current connected with said intermediate terminals, a third and a fourth transformer each having a primary and a secondary winding, a second relay for selectively connecting the plates of said tubes in a push-pull arrangement with the primary of either the third or the fourth transformer, sending means including a microphone for supplying the primary of the first transformer with voice frequencies of a spoken message, receiving means including a receiver for supplying the primary of the second transformer with side band frequencies of a carrier modulated by the voice frequencies of a spoken message, a sending circuit connected with the secondary of the third transformer including a transmitter, a receiving circuit connected with the secondary of the fourth transformer including a loudspeaker, and manually controlled means for governing said first and second relay and so arranged that the voice frequencies of the sending means are translated to side band frequencies of the local carrier in the sending circuit and the side band frequencies of the receiving means are translated to audio frequencies in the receiving circuit.

6. A telephone system comprising, a communication circuit, a receiver, a transmitter, a circuit controller adapted to couple the receiver or the transmitter with said circuit, a microphone, a loud speaker; a frequency translating means including a pair of electron tubes connected in a push-pull arrangement, and a generator of carrier current so coupled with the input circuits of said tubes as to be balanced out in the output circuits of said tubes, a first coupling means for connecting either the receiver or the microphone with the input circuits of the tubes of said translating means, a second coupling means for connecting the output circuits of the tubes of the translating means to either the transmitter or to the loud speaker, and manually controlled means for governing said circuit controller and said first and second coupling means, and arranged in such a manner that voice frequencies produced by speaking into the microphone are delivered to the communication circuit as side band frequencies of the carrier, and side band frequencies of a carrier modulated at voice frequencies received from the communica-

tion circuit are delivered to the loud speaker at corresponding audio frequencies.

7. A telephone system comprising, a communication circuit, a receiver, a transmitter, a circuit controller adapted to couple the receiver or the transmitter with said circuit, a microphone, a loud speaker; a frequency translating means including a pair of electron tubes connected in a push-pull arrangement, and a generator of carrier current so coupled with the input circuits of the tubes that the carrier frequency is balanced out in the output circuits of said tubes; a first relay for coupling either the receiver or the microphone to the input circuits of the tubes of the translating means, a second relay for coupling either the transmitter or the loud speaker with the output circuits of the tubes of the translating means, and manually controlled means for governing the circuit controller and said first and second relay, and arranged in such a manner that voice frequencies produced by speaking into the microphone are delivered to the communication circuit as side band frequencies of the carrier, and side band frequencies of a carrier modulated at voice frequencies received from said communication circuit are delivered to the loud speaker as corresponding audio frequencies.

8. A telephone system comprising, a communication circuit, a receiver, a transmitter, a circuit controller adapted to couple the receiver or the transmitter to said circuit, a microphone, a telephone receiver, a first stage amplifier, a frequency translating means capable of translating voice frequencies to side band frequencies of a carrier or of translating side band frequencies of the carrier to audio frequencies, a second stage amplifier, a first coupling means for connecting the receiver or the microphone to the input of the first stage amplifier, a second coupling means for connecting the output of the first stage amplifier to the input of the translating means, a third coupling means for connecting the output of the translating means to the input of the second stage amplifier, a fourth coupling means for connecting the output of the second stage amplifier to either the telephone receiver or to the transmitter; and manually controlled means to govern said circuit controller and said first, second, third and further coupling means and arranged in such a manner that voice frequencies produced by the microphone are delivered to the communication circuit as amplified side band frequencies of the carrier or side band frequencies received from said circuit are delivered to the telephone receiver as amplified audio frequencies.

9. A telephone system comprising, a communicating circuit, a receiver, a transmitter, a circuit controller adapted to couple the receiver or the transmitter to said communicating circuit, a microphone, a telephone receiver, a first stage amplifier; a frequency translating means including a generator of carrier current, and a pair of electron tubes placed in a push-pull arrangement with the carrier voltage applied to both grids in phase; a band-pass filter, a low-pass filter, a second stage amplifier, a first coupling means for connecting the receiver or the microphone with the input of the first stage amplifier, a second coupling means for connecting the output of the first stage amplifier to the input of the translating means in such a manner that the voltages applied to the two grids are opposite in phase, a third coupling means for con-

necting the output of the translating means to the band-pass filter or to the low-pass filter, a fourth coupling means for connecting the band-pass filter or the low-pass filter with the input of the second stage amplifier, a fifth coupling means for connecting the output of the second stage amplifier with either the telephone receiver or with the transmitter; and manually controlled means to govern said circuit controller and said first, second, third, fourth and fifth coupling means and arranged in such a manner that voice frequencies developed in the microphone are delivered to the communicating circuits as amplified side band frequencies of the carrier or side band frequencies received from said circuit are delivered to the telephone receiver as amplified audio frequencies.

10. A telephone system comprising, a communication circuit, a sending means including a microphone for supplying a voice frequency current, receiving means coupled with said circuit and adapted to pass the side band frequencies of a carrier frequency modulated with voice frequencies, a frequency translating means including a pair of electron tubes having a push-pull arrangement of plate circuits and a generator of said carrier frequency current so connected with the grids of the tubes that the carrier is applied to the grids in phase, circuit controlling means, means including a contact of the circuit controlling means for coupling the sending means with the frequency translating means and arranged that the voice frequency current is applied to the grids of said tubes opposite in phase, means including a contact of the circuit controlling means for coupling the receiving means with the frequency translating means and arranged that the side band frequencies are applied to the two grids opposite in phase, a receiving circuit including a loud speaker, a sending circuit including a transmitter capable of supplying current to the communication circuit, means including a contact of the circuit controlling means for coupling the receiving circuit with said plate circuits, other means including a contact of the circuit controlling means for coupling said sending circuit with said plate circuits, and a manually controlled device for selectively operating said circuit controlling means, whereby voice frequencies produced in the microphone are transmitted to the communication circuit as side band frequencies of the carrier or the side band frequencies received from the communication circuit are effective to operate the loud speaker.

11. In combination, a communication circuit, a source of periodic signaling current, a receiver AR coupled with said circuit effectively influenced by periodic signaling current, an amplifier including an electron tube, a signaling device LS responsive to periodic signaling current, a transmitter AT coupled with the communication circuit for supplying current thereto, circuit controlling means, means including a first set of contacts of said circuit controlling means for coupling said periodic current source and said transmitter with the grid and plate circuits of the tube of the amplifier respectively, other means including a second set of contacts of the circuit controlling means for coupling said receiver and said signaling device with the grid and plate circuits of said tube respectively, and manually controlled means to operate said circuit controlling means for selectively closing said first and second set of contacts.

12. In combination, a communication circuit extending from a location, a source of periodic signaling current and a transmitter AT coupled with said circuit at said location, a signaling device LS responsive to periodic signaling current and a receiver AR coupled with said circuit at said location, an electron tube having a grid and a plate, control means having circuit controlling contacts, means including a first set of contacts of the control means for connecting said source and transmitter with the grid and plate of said tube respectively for supplying such signaling current to said circuit, other means including a second set of contacts of the control means for connecting said receiver and said signaling device with the grid and plate of the tube for picking up such signaling current from said circuit, and means to operate said control means for selectively closing said first and second set of contacts.

13. A telephone system comprising, a communication circuit, sending means including a source of current and a telephone transmitter, a sending circuit including means coupled with the communication circuit, receiving means coupled with said communication circuit, a receiving circuit including a current source and a telephone receiver, an amplifier including an electron tube having a grid and a plate, control means including a plurality of circuit controlling contacts, means including a first and a second contact of the control means for coupling said sending means and said sending circuit with the grid and plate of the tube respectively for supplying a telephone current to the communication circuit, other means including a third and a fourth contact of the control means for coupling said receiving means and said receiving circuit with the grid and plate of the tube respectively for picking up a telephone current from the communication circuit, and manually operated means for governing the control means to selectively close either said first and second contacts or said third and fourth contacts.

14. A telephone system comprising, a communication circuit, an inductor coupled with said circuit, sending means including a current source and a microphone, a receiving circuit including a loud speaker, an amplifier including an electron tube having a grid and a plate, control means including a plurality of circuit controlling contacts, means including a first and a second contact of said control means for connecting said inductor and said loud speaker with the grid and plate of said tube respectively for picking up a telephone current from the communication circuit, other means including a third and a fourth contact of the control means for connecting said sending means and said inductor with the grid and plate of said tube respectively for supplying a telephone current to the communication circuit, and manually operated means for governing the control means to selectively close either said first and second contacts or said third and fourth contacts.

15. In combination, a communication circuit, an inductor coupled with said circuit, an amplifier including an electron tube, a plate and a grid circuit for said tube, control means including a plurality of contacts, means including a first contact of said control means for coupling said inductor with the grid circuit of said tube for amplifying current picked up from the communication circuit, other means including a second contact of the control means for coupling said inductor with the plate circuit of said tube for supplying cur-

rent amplified by said tube to said communication circuit, and means for governing said control means to selectively close said first and second contacts.

16. A telephone system comprising, a communication circuit, sending means including a microphone, receiving means including a loud speaker, an amplifier including an electron tube, a plate and a grid circuit for said tube, control means including a plurality of circuit controlling contacts, means including a first and a second contact of the control means for coupling the grid and plate circuits of said tube with the communication circuit and said receiving means respectively for amplifying and reproducing a telephone current picked up from the communication circuit, other means including a third and a fourth contact of the control means for coupling the grid and plate circuits of the tube with the sending means and the communication circuit respectively for amplifying and supplying a telephone current to said circuit, and manually operated means for governing said control means.

17. In combination, a communication circuit extending from a location, a source of periodic signaling current and a signaling device responsive to periodic signaling current at said location, an amplifier including an electron tube having a grid element and a plate element, circuit controlling means capable of assuming a first and a second condition, means governed by said circuit controlling means and including a first and a second contact each closed in the first condition to effectively couple the communication circuit and the signaling device to the grid and plate elements of the tube respectively, other means governed by said circuit controlling means and including a third and a fourth contact each closed in the second condition to effectively couple the source of periodic current and the communication circuit to the grid and plate elements of the tube respectively, and manually operable means effective to selectively establish the first and second conditions of said circuit controlling means.

18. In combination with a frequency translating means including a pair of electron tubes which are provided with push-pull grid circuits and with push-pull plate circuits together with a source of carrier frequency current connected across the grids and cathodes of said tubes in parallel, a communication circuit, a source of periodic signaling current, a signaling device responsive to such periodic signaling current, circuit controlling means capable of assuming a first and a second condition, means governed by said circuit controlling means and including a first and a second contact each closed in the first condition to effectively couple the communication circuit and said signaling device to the grid circuits and plate circuits of said electron tubes respectively, other means governed by said circuit controlling means and including a third and a fourth contact each closed in the second condition to effectively couple the source of periodic signaling current and the communication circuit to the grid circuits and plate circuits of said tubes respectively, and manually operable means effective to selectively establish the first and second conditions of said circuit controlling means.

19. In combination, a frequency translating means including a source of carrier frequency current and a first and a second circuit network, said first circuit network operative to modu-

75

late the carrier with a periodic signaling current supplied to its input terminals and to deliver a side band of such modulated carrier to its output terminals, said second circuit network 5 operative to mix such side band supplied to its input terminals with said carrier and to deliver only the periodic signaling frequencies to its output terminals, a communication circuit, a source of such periodic signaling current, a signaling device responsive to such signaling current, circuit controlling means capable of assuming a first and a second condition, means governed by said circuit controlling means and including a first and a second contact closed in the first condition for effectively connecting the communica-

tion circuit and the signaling device with the input and output terminals of said second network respectively, other means governed by said circuit controlling means and including a third and a fourth contact closed in the second condition for effectively connecting the source of periodic signaling current and the communication circuit with the input and output terminals of said first network respectively, and manually operable means effective to selectively establish the 10 first and second condition of said circuit controlling means.
